Attorney.

UNITED STATES PATENT OFFICE.

JOSEPH DOMINGO Y CAÑELLAS, OF NICE, FRANCE.

DESIGN FOR A COMBINED SPOON AND FORK.

58,881.

Specification for Design.

Patented Sept. 6, 1921.

Application filed May 31, 1921. Serial No. 473,901. Term of patent 14 years.

To all whom it may concern:

Be it known that I, JOSEPH DOMINGO Y CAÑELLAS, a subject of the King of Spain, and a resident of Nice, France, have invented a new, original, and ornamental Design for a Combined Spoon and Fork, of which the following is a specification, reference being had to the accompanying drawing, forming part thereof.

The figure is a front view of my combined spoon and fork, showing my new design.

I claim:

The ornamental design for a combined spoon and fork, as shown.

JOSEPH DOMINGO Y CAÑELLAS.
